FREQUENCY ADJUSTING SYSTEM

Louis A. Gebhard and Corrie F. Rudolph, Washington, D. C.; said Gebhard assignor to Wired Radio, Inc., New York, N. Y., a corporation of Delaware

Application April 18, 1930, Serial No. 445,416

8 Claims. (Cl. 250—17)

Our invention relates broadly to frequency adjusting systems and more particularly to a frequency changing system for short wave radio transmitters.

5 One of the objects of our invention is to provide a compact arrangement of frequency adjusting system for short wave transmitters wherein tuning adjustments may be effected simultaneously in a multiplicity of circuits connected with 10 a transmitter.

Another object of our invention is to provide a compact arrangement of frequency changing apparatus in which the inductance in a multiplicity 15 of circuits in the transmitter may be simultaneously changed for adjusting the operating frequency of the transmitter with a minimum number of controls.

A further object of our invention is to provide 20 a method of mounting a multiplicity of inductance units adjacent the parts of the transmitting apparatus by which selected portions of prearranged stationary inductance units may be effectively connected in one portion of the transmitter circuits, while other inductance units 25 may be movably shifted into connection with other parts of the transmitter circuits in adjusting the transmitter circuits for operation upon selected frequencies.

A still further object of our invention is to 30 provide a frequency changing system for short wave transmitters in which connections may be simultaneously established between parts of a transmitter circuit and selected fixed inductance units, and connections established by movably 35 interchanging other inductance units in other portions of the transmitter circuit.

Other and further objects of our invention reside in the assembly of the tuning elements in a high frequency transmitter as set forth more 40 fully in the specification hereinafter following by reference to the accompanying drawings, in which:

Figure 1 schematically illustrates the arrangement of the fixed inductance units and movable 45 inductance units in a high frequency transmitter; Fig. 2 is a side elevation showing the assembly of the fixed removable inductance units in the frequency changing portion of a short wave transmitter constructed according to our invention; 50 and Fig. 3 is a detailed cross-sectional view showing one arrangement of fluid cooled fixed inductance units employed in the transmitter system of our invention.

In high frequency radio transmitters covering 55 a relatively wide frequency band it is necessary

to arrange inductances both in the input and output circuits of each stage of amplification. These inductances must be changed for operation of the transmitter at different frequencies. The frequency change operation must often be made quickly and we have therefore designed a frequency change system for high frequency transmitters wherein both the input and output inductance coils may be switched simultaneously into or out of the amplifier circuits. We have 10 found that a more compact arrangement may be made within the transmitter frame by mounting certain of the inductance coils for rotation on a selecting frame whereas others of the coils are mounted in fixed position and are provided 15 with taps to which selected connection may be made by the simultaneous movement of the switching mechanism.

It is particularly desirable that coils consisting of tubular conductors to conduct cooling fluid 20 should be mounted in fixed position. The frequency adjusting system here disclosed is well adapted for use with the system disclosed in the Reissue Patent No. 18,070 to Louis A. Gebhard, wherein inductances 11 and 18 are to be 25 interchanged by the system disclosed in the present application.

Referring to the drawings in more detail, reference character 1 designates the tuning condensers for the transmitter which are supported 30 concentrically around the electron tube jackets 2, which jackets carry electron tubes 3. The assembly of tube jackets, electron tubes, and tuning condensers is supported by means of insulated frame 4 extending from the framework of 35 the radio transmitter. The input circuit inductance coils are indicated at 5 carried by a rotatable frame 6. The frame 6 has a plurality of radially extending arms which support inductances 40 of selected frequency characteristics in the ends thereof. Each inductance 5 is provided with radially extending blades which may be brought into connection with sets of fixed blades 8 which 45 may connect to the input circuits of the high power tubes 3 through circuits including the input tuning condenser 9 and the tuning condensers 1. The changing of the coils 5 is accomplished by means of the crank 10 which connects to shaft 7 which in turn supports the frame 6. The shaft 7 is suitably journaled in the frame 30 of the transmitter. The inductance coils 5 may have 50 coupling coils 29 extending therethrough to provide an inductive connection to the selected coils 5. The shaft 7 is constructed of insulating material which connects with the bevel gear system 55

11. An auxiliary shaft 12 is driven through the bevel gear system 11 and imparts motion to bevel gear system 13 which drives shaft 14. The shafts 12 and 14 are suitably supported in bearings mounted upon the frame 30 of the transmitter. The shaft 14 is broken by insulated portions 15 and 16 which are mounted in bearings 19 and 20 supported from the condenser structures 1. The insulated portions 15 and 16 are interconnected by link member 17. The insulated portion 16 of the insulated shaft carries the shaft portion 18. The switch blades 21 and 21a are carried by the link portion 17 and the shaft 18. The switch blades 21 and 21a have flexible brushes 22 and 22a supported thereon and these brushes successively engage with contacts 23 and 23a on the output inductance coils 24. We have illustrated a multiplicity of output coils 24, 24b and 24c fixed in position with respect to the switching apparatus and arranged with sets of contacts by which a selected inductance may be connected in the transmitter circuit. Coils 24 may consist of only three turns approximately one foot in diameter, in short-wave transmitters. In such short-wave apparatus, it is highly important that the coil leads be very short, and the construction which we have provided is very effective for this purpose, as well as providing a compact arrangement which can be mounted in small space. In push-pull systems of the type shown in the Reissue Patent No. 18,070 of Louis A. Gebhard, dated May 19, 1931, it is important that the cross connections of the input shall be in close proximity to the tube units and symmetrically arranged with respect thereto, and the system of our invention serves this purpose to good advantage.

For the purpose of explaining our invention, we have shown three end coils at 24, 24b and 24c, each of the coils having separate sets of contacts with which the moving switch blade may establish connection. The inductance coil 24 has radially positioned contacts 23 and 23a and is supported by bracket 26 on support 27 which is attached to the frame 30. Bracket 26b extends from the support 27 and carries the inductance coil 24b. Sets of contacts 23b are carried by the inductance coil 24b arranged at such an angle with respect to the movement of the switch blades 21 and 21a as will enable sliding contact to be established with the switch blades. Inductance coil 24c is carried by bracket 26c which extends laterally from the support 27 on frame 30. Contacts 23c extend from the inductance 24c in such an angular direction that connection may be established by angular movement of the sets of switch blades 21 and 21a to selected positions. The brackets 26, 26b, and 26c are all suitably insulated in order to suspend the associated inductance coils in proper relation with the frame of the transmitter. The brackets are of varying lengths in order to support the inductance coils in an arcuate path about the rotatable members 17 and 18. In one position, the switch blades 21 and 21a are not connected with contacts on an inductance coil. This position is shown in dotted line at 28 in Fig. 1, and in this position a coil not shown in the drawings is connected between the anodes of the two tubes 3, and the stationary mounting of the several inductance coils 24, 24b, and 24c enables these coils to be fluid cooled as illustrated, for example, in Fig. 3 where the coil 24 is shown in cross-section as constituted by hollow tubing through which cooling water circulates. The lowest frequency range of the trans-

mitter is established by the permanently connected coil which connects between the anodes of the tubes 3. The other frequency settings for the transmitter are obtained by the parallel connection of the selected inductance in some one of the other coils 24, 24b, or 24c in accordance with the selected transmission frequency.

The operation of the brushes 22 and 22a is timed through the system of shafts 12 and 12a so that the movement of the switches is coordinated with the shifting in position of the inductances 5. That is to say, simultaneous control in the movement of the inductances 5 into or out of the transmitter circuit is timed with respect to the corresponding movement of the brushes 22 and 22a. A shift in position of the movable inductance coils 5 is accompanied by a similar shift in position of the brushes 22 and 22a so that a particular coil 5 is selected simultaneously with the connection of a selected inductance 24, 24b, or 24c in the transmitter circuit.

While we have illustrated four inductance coils carried by a rotatable frame, it will be understood that a multiple of such coils may be provided and correspondingly any required number of fixed inductance coils may be provided to selectively cover a wide frequency band.

While we have described our invention in one of its preferred embodiments, we desire that it be understood that modification may be made and that no limitations upon our invention are intended other than are imposed by the scope of the appended claims.

What we claim as new and desire to secure by Letters Patent of the United States is as follows:

1. In a high frequency transmission system, electron tube stages having input terminals and output terminals, a multiplicity of tunable circuits, a plurality of fixed output inductance units of different frequency characteristics, contacts extending from each of said fixed inductance units, a selective switch connectible to the contacts of any one of said fixed inductance units, a movable frame structure, input inductance units each having projecting contacts thereon and supported by said movable frame structure, a set of fixed contacts engageable with the contacts carried by the input inductances on said movable frame structure, circuits interconnecting said switching system and said fixed contacts, the number of said output inductance units and contacts therefor being one less than the number of said input inductances, and a control system interconnecting said switching system and said movable frame structure for simultaneously shifting said movable frame structure and operating said switching system for the selective operation of said transmitter circuits on a particular signaling frequency, for connecting one of said output coils to said switch for each position except one of said movable frame which connects an input coil to said fixed contacts.

2. The combination in accordance with claim 1 in which said output inductance units each comprise a helical fluid cooling tubing.

3. The combination in accordance with claim 1 in which said output inductance units each comprise a fluid cooling helical tubing and in which said control system comprises a plurality of rotatable shafts interconnected by gearing, and a manual device for imparting rotary motion to said shafts.

4. A high frequency transmitter construction comprising, an electron tube stage having input and output circuits, a selective input inductance

system comprising a rotatable frame member carrying a set of helical inductance units for movement through an arcuate path, stationary contacts connected in said input circuit of said 5 electron tube stage and disposed in proximity to said arcuate path, and contacts mounted on each of said inductances for engaging with said stationary contacts when said inductances are moved through said arcuate path for selectively 10 interconnecting desired ones of said inductances in said input circuit; a second set of inductances each carrying contacts thereon, stationary mounting means for supporting said second set of inductances to cause said contacts thereon to 15 project into an arcuate path, said second set of inductances each comprising a helical tubing for the conduction of cooling fluid therethrough, a rotatable contacting device mounted for arcuate movement for selectively engaging said contacts 20 of said second set of inductances for connecting the same in the output circuit of said electron tube stage, and mechanical means for simultaneously and conjointly moving said rotatable device and said rotatable frame member for selectively 25 connecting said inductances respectively in the input and output circuits of said electron tube stage.

5. A combination in accordance with claim 4 in which the number of inductance units in said

first mentioned set of inductances is greater than the number of inductances in said second mentioned set of inductances.

6. A combination in accordance with claim 4 in which said electron tube stage includes a condenser partially enclosing an electron tube, and in which said rotatable switching device is supported from said condenser. 5

7. A combination in accordance with claim 4 in which said electron tube stage includes a condenser structure and in which said rotatable switching device is supported from said condenser structure, said rotatable switching device including a plurality of axially aligned conductive elements electrically insulated from each other. 10 15

8. A combination in accordance with claim 4 in which there are a different number of inductances in each of said sets, and in which said electron tube stage comprises a condenser surrounding a high power tube, said rotatable 20 switching device being supported from said condenser and including a plurality of axially aligned contact members electrically insulated from each other, and said mechanical means comprising a plurality of intergeared shafts and a hand crank 25 for actuating the same. 25
